UNITED STATES PATENT OFFICE.

PHILIP C. WAITE, OF OSHKOSH, WISCONSIN.

RUG AND STRAND THEREFOR.

Application filed March 11, 1927. Serial No. 174,503.

This invention relates to a rug which is preferably built up of centrally arranged strands which are edge stitched together, although the rug might be built up from a 5 continuous strand spirally arranged, as is common in the making of rugs of this general character.

In order to give distinctness and character to the pattern, it is necessary that the 10 individual strands be of sufficient width and body to clearly and strikingly display the intended pattern, and the rug strand of the present invention is designed to afford sufficient width to conform to the above requirements which strikingly distinguish the 15 completed rug of the present invention from rugs of the so-called hit or miss type in which no clearly defined pattern is displayed.

20 In the drawings:

Figure 1 is a plan view of a rug illustrating the features of the present invention;

Fig. 2 is an enlarged detail showing two of the strands edge stitched together;

25 Fig. 3 is a section of one of the constituent braids which are spirally overlapped to build up a strand;

Fig. 4 is a cross sectional view through one of the strands; and

30 Fig. 5 is a diagrammatic view intended to more clearly illustrate the method of spirally overlapping the braids.

Each of the rug strands comprises two 35 flattened braided sections A which are spirally overlapped together, as diagrammatically illustrated in Fig. 5, which gives to the completed strand a flat twisted character, differing, however, from an ordinary twist in that the width of the strand is much 40 greater than the thickness, so that there will be a maximum exposure of the flat surfaces of the braids on both sides of the rug strand.

Each of the flat braids A comprises a pair of cores 10 which may be of cotton 45 or other relatively cheap filling material adequate to give a proper body to the braids, and between and around the cores 10 are braided a plurality of covering yarns 11 which are preferably of wool or other suitable surfacing material, which covering 50 yarns are closely spaced to completely conceal the cores, so that the surface of the braid will be of wool, yarn or other material of superior quality.

55 In order to hold the constituent braids in

spirally overlapped relation and to secure a close integration of the two braid constituents composing a single strand, it is preferred to run a line of stitching 12 along the center of each strand, although this may 60 be omitted in some cases. In order to secure a clearly defined pattern in the completed rug, it is, in some cases, desirable to employ in each strand a pair of braids of contrasting color, so that the completed 65 strand will alternately display the colors in the form of diamond shaped patches clearly defined or marked off by the contrast of colors, as indicated in Fig. 2.

In building up a rug from the broad flat 70 strands of the character described, adjacent strands are laid in edgewise relation and united by criss cross stitching 13, and a variety of color schemes or patterns can be secured. Adjacent strands of the same 75 color combination may be so laid as to present continuous cross stripes of the same color, as indicated in Fig. 2, or the adjacent strands can be arranged to bring the patches of contrasting color into edgewise alignment which will give the effect, in the completed rug, of diamond shaped patches of 80 one color, in contrasting relation on all sides with patches of another color.

As shown in Fig. 1, the two marginal 85 strands are arranged in such way as to produce the color patch effect by the employment of strands each composed of sharply contrasting braids. The next two strands afford a less prominent pattern displayed 90 by employing in each strand a pair of braid constituents of more neutral or less highly contrasted colors. The next two strands show the stripe effect secured by registering the color patches to carry the same color 95 continuously across a pair of the strands and so on.

Furthermore, variegated or mottled effects can be secured by the use of parti-colored 100 yarns in individual braids where it is neither desired to produce a dead uniformity in color tone, nor to provide a sharply outlined pattern effect, such mottled tones can be used with advantage in the intermediate portions of the rug with more sharply defined pattern effects confined to the border and central portions of the rug. Obviously, the method of forming the individual strands of the present invention is one which readily lends itself to a multiplicity of pattern 105 110

schemes which may be employed in the producing of striking and highly pleasing patterns in the completed rug.

At the same time, a rug built up in the manner described will possess highly desirable wearing qualities in view of the fact that the closely braided surface yarns completely overlie and conceal the filler, and, at the same time, the manner of spirally overlapping the braids affords a relatively thick and firm body through the rug and so inter coils the braids that they will lie in protective contact with one another, thereby preserving the edges against abrasive action and tending to give long wearing qualities to the rug. While the twisted strands are shown as composed of braided sections, it is not the intention to limit the invention thereto, since the flat strand constituents might be otherwise built up than by braiding.

I claim—

1. A rug strand composed of a plurality of flat braids both spirally coiled together with the convolutions lying flatwise over and under one another, each flat braid comprising a pair of core sections having yarns braided in and out around the core sections, and a central line of stitching passing through the alternately overlapped flat braids for holding the braids in flat coiled relation and the braids being alternately displayed on the same side of the strand as parallel diagonally extending uninterrupted stripes, substantially as described.

2. A rug composed of a plurality of adjacent strands edge stitched together, each strand being composed of a pair of flat braids both spirally coiled together with the convolutions extending diagonally and lying flatwise over and under one another, and the constituent braids of each strand being contrastingly colored and displaying broad parallel uninterrupted stripes of contrasted color extending diagonally from side to side of the strand, substantially as described.

3. A rug composed of a plurality of adjacent strands edge stitched together, each strand being composed of a pair of flat

braids both spirally coiled together with the convolutions extending diagonally and lying flatwise over and under one another, and the constituent braids of each strand being contrastingly colored and displaying broad parallel uninterrupted stripes of contrasted color extending diagonally from side to side of the strand, various portions of the rug being formed of contrastingly colored strands to produce a clearly defined pattern effect, substantially as described.

4. A rug strand composed of a plurality of flat braids both spirally coiled together with the convolutions lying flatwise over and under one another, and a central line of stitching passing through the alternately overlapped flat braids for holding the braids in flat coiled relation, and the braids being alternately displayed on the same side of the strand as parallel diagonally extending uninterrupted stripes, substantially as described.

5. A rug strand composed of a plurality of flat braids both spirally coiled together with the convolutions lying flatwise over and under one another, each flat braid comprising a pair of core sections having yarns braided in and out around the core sections, the braids occupying a flat coiled relation to one another and being alternately displayed on the same side of the strand as parallel diagonally extending uninterrupted stripes, substantially as described.

6. A rug composed of a plurality of adjacent strands edge stitched together, each strand being composed of a pair of flat constituents, both spirally coiled together with the convolutions extending diagonally and lying flatwise over and under one another, and the constituents of each strand being contrastingly colored and displaying parallel uninterrupted stripes of contrasting color extending diagonally from side to side of the strand and constituting color patches forming ingredients of a clearly defined pattern effect, substantially as described.

PHILIP C. WAITE.
